UNITED STATES PATENT OFFICE.

EUGENE H. TAYLOR, OF BOSTON, MASSACHUSETTS.

TIE-PLATE AND RAIL CLAMP.

1,174,639.

Specification of Letters Patent.

Patented Mar. 7, 1916.

Application filed November 3, 1915. Serial No. 59,468.

To all whom it may concern:

Be it known that I, EUGENE H. TAYLOR, a citizen of the United States, residing at Boston, county of Suffolk, State of Massachusetts, have invented a certain new and useful Improvement in Tie-Plate and Rail Clamps, of which the following is a specification, reference being had therein to the accompanying drawings.

10 My invention relates to an improvement in tie plate and rail clamps which are employed for securing steel rails to railroad ties or the like.

15 It has for its object the production of a rail clamp which may be readily secured to the rail and be used in connection with a tie plate for effectually preventing the rail from creeping. It is so arranged and constructed that the clamp may be applied to 20 the rail without making it necessary to put together detached clamping members thereby saving much time and labor in laying the track.

25 My invention will be fully understood from the following description when taken in connection with the accompanying drawings and the novel features thereof will be pointed out and clearly defined in the claims at the close of the specification.

30 In the drawings, Figure 1 is a top plan view of a portion of a rail and a device embodying my invention. Fig. 2 is a section on line 2—2 of Fig. 1. Fig. 3 is a view in perspective of the clamp shown in Figs. 1 35 and 2. Fig. 4 is a view of a modified form of clamp embodying my invention.

Having reference to the drawings there is shown at 11 a metal tie plate having notches 13 and holes 12 which are adapted 40 to receive spikes or other equivalent means for securing the tie plate to a railroad tie or other like support. The tie plate 11 is provided with a rectangular opening 14 which is somewhat longer than the width of 45 the base 15 of the rail to be employed and is adapted to receive the clamp.

The clamp consists of a shank or strip of metal 16 which is substantially equal in thickness to that of the tie plate and which 50 has a width and length slightly less than that of the rectangular opening 14 so that it is adapted to fit loosely within the opening and rest upon the tie. At one end of the shank 16 is a clamping member 17 which 55 projects upwardly therefrom and is pro-

vided on its inner or clamping surface with a concave portion 18 adapted to fit over the edge 19 of the base 15 of the rail. The upper end of the clamping member 17 is beveled as shown at 20 in order to facilitate 60 inserting the base 15 of the rail within the clamping member as will be described. The other end of the shank 16 is provided with a clamping member 21 which in my preferred form is separated from the shank 65 but is at all times secured to it by a screw or bolt 22 which in the particular form shown in the drawings, passes through an elongated hole 23 in the member 21 and engages with a threaded hole in the shank. 70 The clamping member 21 which is secured to the upper surface of the shank 16 near one end thereof is provided with a beveled end 24 which co-operates with a bevel 25 on the upwardly projecting portion 26 of the 75 shank. The inner end 27 of the clamping member 21 is provided with a bevel 28 which is adapted to singly fit over the edge of the base 15 of a rail. The bevels 24 and 25 are so arranged that when the screw bolt 80 22 is turned down the clamping member is forced inwardly on the shank 16 as well as downwardly. By this arrangement the clamping members 21 and 17 may be 85 brought together by the screw bolt 22 and 90 forcibly clamped about the edge of the base 95 of the rail.

In practice the clamp is placed over the edges of the base of a rail, is inserted in the opening 14 in the tie plate 11, and the screw bolt 22 is turned down to clamp the members 17 and 21 firmly over the edges of the rail base. The rail is then positioned and the tie plate spiked to the tie or other rail support. The clamping members 17 and 21 are so arranged that it is not necessary 100 to detach the member 21 from the shank in order to place the clamp over the base of the rail. This is effected by the arrangement of the bevels 24 and 25 and the clamping member 21 and the upwardly projecting portion 26 respectively, and by the bevel 20 on the clamping member. When the screw bolt 22 is loosened the bevels 24 and 25 allow the clamping member 21 to be 105 moved away from the clamping member 17 sufficiently to permit the base 15 of the rail to be inserted within the clamp, the bevel 20 being so shaped that when one edge of the base is inserted beneath the bevel 28 of 110

the loosened clamping member 21 the clamping member 17 may be sprung over the other edge of the base. This may be readily done by tapping the clamp with a hammer 5 or the like. I regard this as an important feature of my invention for by this arrangement I have eliminated the necessity of putting together detached parts and thereafter adjusting them about the base of 10 the rail.

In Fig. 4 I have shown a modified form of device. The clamp shown consists of a shank 29 composed of spring metal such as steel. It is provided with a clamping 15 member 30 at one end which is similar in construction to the clamping member 17 described above. The other end of the shank 29 is however bent back upon itself to form a clamping member 31 which is normally at a slight angle to the shank and which is adapted to be sprung toward the same by a screw bolt 32 which passes loosely through a hole in the clamping member 31 and engages with a threaded 20 hole in the shank 29. The spring clamping member 31 has a bevel 33 at its inner end which is adapted to engage with an edge of the rail base. It is effectively pivoted at the end of the shank so that when the screw 25 bolt 32 is turned down the bevel 33 is forced downwardly toward the upper surface of the shank 29 and at the same time inwardly toward the clamping member 30. The parts are so arranged that when the 30 screw bolt 32 is loosened the clamp may be readily sprung over the base of the rail owing to the shape of the bevel 34 on the member 30, which is similar to the bevel 20 on the member 17 above described and 35 also to the ability of the clamping member 31 to yield upwardly when pressure is exerted against the bevel 33.

What I claim is:

1. The improved tie plate and clamp comprising a tie plate having an opening therein, a clamp adapted to fit in said opening, said clamp consisting of a shank of metal having a clamping member at one end, a clamping member on the upper side 45 of said shank and at the other end thereof which is spaced apart from the said shank and adapted to move toward and away from the same, and means for moving said movable clamping member toward said shank 50 to cause said clamp to engage the edges of a base of a rail.

2. The improved tie plate and clamp comprising a tie plate having an opening therein, a clamp adapted to fit in said opening comprising a shank of metal, having a clamping member at one end and an upwardly projecting portion at the other end, a second clamping member in engagement 55

with said upwardly projecting portion and adapted to move toward and away from 65 said shank, and means for moving said clamping member toward said shank to cause said clamp to engage the edges of a base of a rail.

3. The improved tie plate and clamp 70 comprising a tie plate having an opening therein, a clamp adapted to fit in said opening consisting of a shank of metal having a clamping member at one end, a beveled upwardly projecting portion at the other 75 end of said shank, a second clamping member spaced apart from said shank having a bevel adapted to coöperate with the bevel on said upwardly projecting portion to cause said second clamping member to move 80 toward said first clamping member when moved toward said shank and to allow it to be moved away from said first clamping member when moved away from said shank, and means for moving said second 85 clamping member toward and away from said shank.

4. The improved tie plate and clamp comprising a tie plate having an opening therein, a clamp adapted to be received 90 within said opening, said clamp consisting of a shank having a clamping member at one end, an upwardly projecting portion at the other end, said upwardly projecting portion having a bevel extending upwardly and 95 outwardly from the upper surface of said shank, a clamping member having a hole therethrough and a bevel at one end corresponding with the bevel on said upwardly projecting portion, and a screw passing 100 loosely through the hole in said clamping member into said shank.

5. The improved tie plate and rail clamp comprising a tie plate having an opening therein, a clamp adapted to be received 105 within said opening consisting of a shank having a clamping member at one end and an upwardly projecting portion at the other end, said upwardly projecting portion having an upwardly and outwardly inclined bevel and said clamping member having a bevel at the upper end substantially at right angles to the bevel on said upwardly projecting portion, a second clamping member spaced apart from the upper 110 surface of said shank and having a bevel coöperating with the bevel on said upwardly projecting portion, and means for moving said second clamping member toward and 115 away from said shank.

In testimony whereof I affix my signature, in presence of two witnesses.

EUGENE H. TAYLOR.
